ADOLPH RUBIN, OF ST. LOUIS, MISSOURI, ASSIGNOR TO SIEBER PRODUCTS MFG. CO.,
OF ST. LOUIS, MISSOURI, A CORPORATION OF MISSOURI.

CORRUGATING MACHINE.

1,420,060.

Specification of Letters Patent. Patented June 20, 1922.

Application filed October 20, 1919. Serial No. 331,777.

To all whom it may concern:

Be it known that I, ADOLPH RUBIN, a citizen of the United States, residing at St. Louis, Missouri, have invented a certain 5 new and useful Improvement in Corrugating Machines, of which the following is a full, clear, and exact description, such as will enable others skilled in the art to which it appertains to make and use the same.

10 This invention relates to machines of the kind that are used for pressing grooves or corrugations in sheet material.

The main object of my invention is to provide a machine of simple construction 15 for corrugating a sheet of paper that is adapted to be used in a loose leaf binder so as to form a hinge portion on the sheet that facilitates the turning of the sheet when it is clamped in operative position in the 20 binder.

Another object is to provide a corrugating machine of novel construction that can be adjusted easily to adapt it to sheets of different thicknesses or to vary the depth 25 of the grooves or corrugations formed in the sheet.

Other objects and desirable features of 30 my invention will be hereinafter pointed out.

Figure 1 of the drawings is a top plan view of my improved corrugating machine. Figure 2 is a rear elevational view.

Figure 3 is a vertical sectional view, taken on the line 3—3 of Figure 2, looking in the 35 direction indicated by the arrows; and

Figure 4 is a vertical sectional view, taken on the line 4—4 of Figure 1, looking in the direction indicated by the arrows, the gears and pulleys being shown in elevation.

40 Referring to the drawings which illustrate a machine constructed in accordance with my invention and designed to be used for corrugating the rear edge portion of a sheet of paper that is adapted to be used in a loose leaf binder, A and B designate a pair of grooved rolls between which a sheet 45 α of paper is adapted to be passed so as to form a corrugated portion γ on one edge of said sheet, and C designates a table or

50 work support on which the sheet is supported preferably while it is being fed to the rolls A and B, as shown in Figure 1. The rolls A and B are connected to shafts 1 and 2, respectively, that are journaled in 55 a stationary supporting structure D, which

shafts are connected together by gears 3, as shown in Figure 4, so that when power is applied to the shaft 1 the shaft 2 will rotate in unison with same, the shaft 1 being provided with a fixed pulley 4 and a loose pulley 4^a, so as to enable said shaft to be driven by a belt (not shown). One of the shafts just referred to is mounted in the supporting structure D in such a manner that it can be adjusted to move the 60 rolls A and B toward and away from each other so as to adapt the machine to sheets of varying thicknesses or to vary the depth of the grooves or corrugations formed in the sheet. In the machine herein illustrated the shaft 1 is journaled in an eccentric bearing E that is oscillatingly mounted in the supporting structure D, said bearing E being adapted to be turned or oscillated in one direction so as to move the roll A 65 toward the roll B and turned or oscillated in the opposite direction so as to separate said rolls or increase the space between same. Various means can be employed for holding the bearing E in adjusted position, but 70 I prefer to provide said bearing with an adjustable screw 5 that projects radially from same through a clamping block 6 that fits in a curved seat 7 in the upper side of the housing 8 on the stationary supporting structure D in which the eccentric bearing E is arranged, said housing being provided with an elongated slot 9, as shown in Figures 1 and 2, so as to provide a clearance for the radially-projecting screw 5 on 75 the eccentric bearing E. To adjust the bearing E it is only necessary to loosen the screw 5, then rotate the bearing E by moving the screw 5 bodily longitudinally of the slot 9, and thereafter tighten said screw so 80 as to clamp the block 6 tightly against the seat 7, and thus hold the bearing E in adjusted position. The gears 3 previously referred to are inclosed by a housing 10 on the stationary supporting structure D, as 85 illustrated in Figure 4. While the particular form of the stationary supporting structure D is immaterial, so far as my broad idea is concerned, I prefer to form said supporting structure from a casting provided 90 with horizontally-disposed flanges 11 to which supporting legs 12 are connected, as illustrated in Figure 3, the gear housing 10, previously referred to, being connected to said casting by removable fastening devices 95

110

13, so as to enable said housing to be removed for inspection or repair of the gears 3. Oil holes 14 are formed in the top of the gear housing 10, in the portion of the 5 casting in which the shaft 2 is journaled and in the eccentric bearing E, as illustrated in Figures 3 and 4, so as to enable a lubricating medium to be supplied to the gears and to the shafts on which the rolls 10 A and B are mounted. The rolls A and B are adjustably mounted on the shafts 1 and 2, respectively, so as to enable said rolls to be adjusted longitudinally of said shafts for the purpose of varying the width 15 of the corrugated portion γ of the sheet. When the roll A is arranged in exact vertical alignment with the roll B said rolls will form a corrugated portion γ on the sheet of the same width as the length of the corrugated faces on said rolls. For example, 20 if the rolls A and B are provided with corrugated surfaces one inch in length, the width of the corrugated portion γ will be one inch wide when said rolls are in exact 25 vertical alignment with each other. If said rolls are shifted out of vertical alignment with each other, however, as illustrated in Figures 2 and 4, the width of the corrugated portion γ on the sheet will be reduced. 30 Assuming that the corrugated surfaces on the rolls are one inch long and that the roll A is adjusted longitudinally of the shaft so that only one half of same laps over the roll B, or, in other words, is arranged in vertical 35 alignment with the roll B, the width of the corrugated portion on the sheet will be one half inch. Any preferred means can be used for adjustably connecting the rolls B to their supporting shafts, the means here- 40 in illustrated for this purpose consisting of a socketed set screw 15 in the hub of each roll whose inner end bears against a flat portion on the supporting shaft of the roll when the screw is tightened, as illustrated 45 in Figure 4. When the machine is used for corrugating very thin paper the rolls A and B have to be set so close together that the teeth on one roll travel in the grooves of the other roll. When the rolls are set in this 50 manner it is necessary to first turn the eccentric bearing E so as to separate the rolls before one roll can be adjusted longitudinally with relation to the other so as to vary the width of the corrugated portion to 55 be formed in the sheet.

In the machine herein illustrated the table C not only supports the sheet α while it is being fed to the corrugating rolls, but it also determines the position of the corrugated 60 portion γ of the sheet with relation to the edge of the sheet. This is accomplished by equipping the table C with a gauge or upwardly-projecting flange 16 against which the edge of the sheet is held while it is being 65 fed to the corrugating rolls A and B and

mounting said table in such a manner that it can be adjusted longitudinally of the roll supporting shafts 1 and 2, so as to move the work gauge 16 towards and away from the co-operating grooved surfaces on the 70 rolls A and B between which the sheet is passed. For example, when the table C is adjusted in the position illustrated in full lines in Figure 1, namely, with the flange or work gauge 16 in alignment with the inner 75 end of the grooved portion of the roll A, the grooved portion γ of the sheet will be located at the extreme edge of the sheet. By adjusting the table C longitudinally of the roll supporting shafts into the position indicated by dotted lines in Figure 1, the work gauge or flange 16 on said table will permit the sheet to assume such a position with relation to the corrugating rolls that said rolls will form a corrugated portion on the sheet 80 some distance away from the edge of the sheet. In the form of my invention herein illustrated the table C is slidably mounted on a horizontally-disposed rod 17 that projects laterally from the stationary supporting structure D of the machine, said table being provided on its underside with lugs 18 having holes in same through which the rod 17 passes and one of said lugs being provided with a set screw 19 that can be screwed 95 tightly against the rod 17 so as to clamp the table in adjusted position, said table being provided at its front end with a supporting leg 20 that holds the table in a horizontal position. In a machine of the construction 100 above described loose leaf sheets and other pieces of sheet material can be grooved and corrugated quickly and accurately. Moreover, the machine can be adjusted easily to vary the depth of the corrugations formed 105 in the sheet or to adapt the machine to sheets of varying thicknesses and it can also be adjusted easily to vary the width of the corrugated portion formed in the sheet and the position of said corrugated portion with relation to the edge of the sheet. 110

Having thus described my invention, what I claim as new and desire to secure by Letters Patent, is:

1. A sheet corrugating machine, comprising- 115 a pair of grooved rolls between which a sheet is adapted to be passed, shafts on which said rolls are mounted, a supporting structure in which one of said shafts is journaled, an adjustable eccentric bearing in said 120 supporting structure in which the other shaft is journaled, a securing means for said eccentric bearing comprising an adjustable screw in said bearing projecting radially therefrom through an elongated slot in said supporting structure and provided with a head and a clamping block interposed between said supporting structure and the head of said screw. 125

2. A sheet corrugating machine, comprising- 130

ing a supporting structure, a pair of shafts journaled in said supporting structure and arranged one above the other, grooved rolls mounted on the ends of said shafts and arranged so that one roll projects forwardly beyond the other, means whereby one of said rolls can be adjusted towards and away from the other roll and also longitudinally of same, and a work table provided with a gauge against which one edge of the sheet bears.

5 A sheet corrugating machine, comprising a supporting structure, a pair of shafts

10 journaled in said supporting structure and provided with grooved rolls between which a sheet is adapted to be passed, means whereby one of said rolls can be adjusted towards and away from the other roll and also longitudinally of same, a rod projecting laterally from said supporting structure, a work table slidingly mounted on said rod and provided with a work gauge against which one edge of the sheet bears, and means for securing said work table in adjusted position.

15 20 ADOLPH RUBIN.
